EVAPORATIVE COOLER CABINET

Myers K. Parsons, 4601 Highland Terrace, Austin, Tex.

Filed Nov. 6, 1961, Ser. No. 67,388

Term of patent 14 years

(Cl. D62—4)

FIG. 1 is an elevational view of an evaporative cooler cabinet showing my new design.

FIG. 2 is a top plan view thereof.

FIG. 3 is a perspective view thereof.

FIG. 4 is a fragmentary vertical sectional view through one side of the casing.

The undisclosed sides of the casing and the side of the air duct opposite that shown in FIG. 1 are substantially the same in appearance as those shown.

I claim:

The ornamental design for an evaporative cooler cabinet, substantially as shown and described.
